[57] CLAIM

A high-fidelity receiver cabinet, or the like, substantially as shown and described.

DESCRIPTION

FIG. 1 is a perspective view of a high-fidelity receiver or the like, showing our new design;
FIG. 2 is an end elevation view thereof;
FIG. 3 is a perspective view, of a high-fidelity receiver with the adjustable lid in a raised position;
FIG. 4 is an end elevation view of the high-fidelity receiver in the position shown in FIG. 3;
FIG. 5 is a top plan view thereof with portions shown fragmentarily in section along line 5—5 of FIG. 3;
FIG. 6 is a rear view thereof with the adjustable lid in the lower position, as in FIG. 1.

FIG. 1

FIG. 2

FIG. 3
